Primary Examiner — Randall Gholson(74) *Attorney, Agent, or Firm* — Dickstein Shapiro LLP(57) **CLAIM**

I claim the ornamental design for a case, as shown and described.

DESCRIPTION

FIG. 1 is a rear view of a case showing an embodiment of our new design; and,

FIG. 2 is a rear perspective view of the embodiment of FIG. 1. The broken lines in FIGS. 1-2 having a dash-dash configuration depict environmental subject matter only and form no part of the claimed design.
